(57) **CLAIM**

The ornamental design for tree grate, as shown and described.

DESCRIPTION

FIG. 1 is a perspective view of the tree grate embodying the new design;

FIG. 2 is a top elevational view thereof;

FIG. 3 is a right side elevational view thereof;

FIG. 4 is a left side elevational view thereof;

FIG. 5 is a front elevational view thereof;

FIG. 6 is a rear elevational view thereof;

FIG. 7 is a top elevational view thereof showing segments of one type of assembled tree grate in broken lines; and,

FIG. 8 is a perspective view thereof showing segments of one type of assembled tree grate in broken lines.

FIGS. 1–8 show portions of a tree grate in broken lines. The broken lines are shown for environmental purposes and form no part of the claimed design.
